PROCESS OF FORMING LENS-BLANKS.

1,370,042.

Specification of Letters Patent.

Patented Mar. 1, 1921.

Application filed March 11, 1920. Serial No. 364,977.

To all whom it may concern:

Be it known that I, HAROLD K. PARSONS, a citizen of the United States, residing at Southbridge, in the county of Worcester and 5 State of Massachusetts, have invented certain new and useful Improvements in Processes of Forming Lens-Blanks, of which the following is a specification.

This invention relates to improvements in 10 lenses and has particular reference to what is commonly termed a bifocal lens.

The leading object of the present invention is the provision of a novel and improved process of economically constructing 15 two part bifocal lenses.

Prior to the present invention it has been customary to form two part bifocal lenses by first grinding a countersink in an individual lens blank and then suitably mounting 20 within this countersink a segment of different index of refraction which may be suitably secured in position either by cementing, by fusion, or the like, after which the blank is ground to the desired prescription 25 curve. This process has hitherto always been an individual one, but a single lens at a time being produced, and requiring the careful grinding of small segments and the like in order that the desired results 30 might be attained.

It is, therefore, one of the principal objects of the present invention to provide an improved process in which a plurality of lenses in place of a single lens may be simultaneously formed with a single fusing or securing operation, in which larger segments easier of grinding may be employed, and in 35 which larger segment portions will be present in the finished lens than has been possible with the method of construction in use prior to the present invention.

With these and other objects in view, therefore, my invention resides in the novel features and steps hereinafter disclosed, and 45 it will be understood that I may make any modifications in the specific details referred to within the scope of the appended claims without departing from or exceeding the spirit of my invention.

Figure I represents a plan view illustrating

ing the relationship of the parts at the completion of the uniting step in my improved process.

Fig. II illustrates in a semi-diagrammatic manner one of the primary steps in my 55 process.

Fig. III represents an intermediate step in the process.

Fig. IV illustrates the splitting of the blank subsequent to uniting of the main and 60 segment portions.

Fig. V is a sectional view illustrating the subsequent grinding of the blank in the production of the semi-finished lens.

Fig. VI represents a plan view of the 65 blank shown in Fig. V.

Fig. VII represents a plan view illustrating the construction of three lenses at a time in place of two.

In the drawings, where I have illustrated 70 the more important steps in the carrying out of my improved process, the numeral 1 designates the major portion of the blanks, having formed therein as at 2 countersinks to receive the segments 3. Prior to my invention this segment has been, in the form of a hollow recess ground in the individual blank. In the carrying out of my improved process, however, I mount in juxtaposition a plurality of blanks shown in Fig. I as 80 two, and in Fig. VII as three, blanks having their edges disposed adjacent each other but arranged in tilted relation. While supported in this position, as by the block 4, they are subjected to a simultaneous abrading action of the grinding lap or tool 5 suitably actuated as by the eccentric 6 and link 7 to swing about the adjustable center point 8, whose position may be varied to dispose it at the radial center of whatever curve is 85 being ground into the countersink, this pivot center being mounted on the vertical slide 9 so that the upper spindle and grinding tool may move downward as the glass is ground away with the radius center being 90 maintained so that the curve produced while preferably being the counterpart of or complementary to the curvature on the tool is controlled by the center point on which the tool arm swings so that the tool is al- 100

- ways kept true and the curve unvaried. At the same time a rotary motion is preferably applied to the block 4 as by suitable driving power applied to the pulley 10 to cause this member to rotate or spin, which in combination with the transverse swinging of the grinding tool provides a very satisfactory break-up motion for proper grinding and polishing as desired of the countersink.
- 10 The parts are thus suitably ground to produce a continuous curve in the adjacent blanks, which curve on account of the tilting of the blanks will be deepest into the blank substantially at the geometrical center 15 of the countersink in each blank and will cut but slightly into the inner edge of the blank to but slightly reduce the blank thickness at that point.

This operation having been completed, the 20 blanks are again supported in substantially the same relationship as previously upon the supporting block 4, when the segment 3 is secured in position either by cementing or fusion or the like. After this operation has 25 been completed the segment is split as on the line IV-IV of Fig. III, for example, to provide the pair of blanks as illustrated cross-sectionally in Fig. IV, each blank having a semi-circular or sector shape segment 30 portion 3 to one side of its major portion, the segment, however, having its thickest portion at the edge, as will be seen by reference to Fig. IV.

The blank having been prepared to this extent, I then form or have formed subsequently on the segment face the prescription curve 12 shown in full lines in Fig. V, which is so ground as to remove the projecting portion 13 of the segment shown in dotted lines and to produce a final finished lens 40 surface substantially as indicated by said full lines 12 appearing in plan as illustrated in connection with Fig. VI of the present drawings, the final lens being suitably cut 45 out from the blank in question, as shown by the dotted lines in Fig. VI illustrating the cutting of a large round eye lens from one of the blanks in question.

It will be understood that the various 50 steps in the process and results obtained are substantially identical when the three blank form shown in Fig. VII is made use of in place of the two blank form particularly described.

55 It is to be understood that the segment 3 is in all ordinary cases of a glass of higher index of refraction than the major blank 1 in order that a difference in focal value of the two portions may be obtained through 60 this difference in index of refraction of the glasses, although in some instances it may be of glass of a lower index of refraction as when the central portion is to be used for distant and the upper portion for 65 near vision work, or it may even be of a

glass of the same index of refraction but having different properties, as when protection from ultra violet or other rays is desired for a particular kind of work.

I claim:

1. The process of forming bifocal lens blanks consisting in supporting a plurality of blanks in tilted relation, simultaneously centrally abrading the composite blank thus formed, supporting the relationship occupied during the grinding operation and simultaneously securing a single segment within the recesses of the several blanks. 70

2. The process of forming bifocal lens blanks consisting in supporting a plurality of blanks in tilted relation, simultaneously centrally abrading the composite blank thus formed, supporting the relationship occupied during the grinding operation, simultaneously securing a single segment within 80 the recesses of the several blanks, and splitting the segment to provide a portion for each individual blank. 85

3. The process of forming bifocal lens blanks consisting in supporting a plurality of blanks in tilted relation, simultaneously centrally abrading the composite blank thus formed, supporting the relationship occupied during the grinding operation, simultaneously securing a single segment within 90 the recesses of the several blanks, splitting the segment to provide a portion for each individual blank, and grinding the segment bearing face of the blank to remove the excess edge thickness of the segment. 95

4. The process of forming lens blanks including forming countersinks in a plurality of blanks, supporting the blanks in relatively tilted relation with their countersinks in juxtaposition, forming a button to fit said 105 countersinks, securing the button within the countersinks, and subsequently splitting the button to provide an individual section remaining with each original blank.

5. The process of forming bifocal lenses 110 consisting in supporting a plurality of blanks in tilted relation with their edges in juxtaposition, simultaneously grinding the adjacent portions of the several blanks, maintaining the blanks in tilted relation, 115 and simultaneously filling the countersinks formed by grinding with a portion of glass of a different index of refraction.

6. The process of forming bifocal lenses 120 consisting in supporting a plurality of blanks in tilted relation with their edges in juxtaposition, simultaneously grinding the adjacent portions of the several blanks, maintaining the blanks in tilted relation, 125 simultaneously filling the countersinks formed by grinding with a portion of glass of a different index of refraction, and subsequently separating the blanks and filler.

7. The process of forming bifocal lenses 130 consisting in supporting a plurality of

blanks in tilted relation with their edges in juxtaposition, simultaneously grinding the adjacent portions of the several blanks, maintaining the blanks in tilted relation, simultaneously filling the countersinks formed by grinding with a portion of glass of a different index of refraction, subsequently separating the blanks and filler, and grinding the

individual blanks after separation to remove the central excess portion of the filler. 10

In testimony whereof I have affixed my signature, in presence of two witnesses.

HAROLD K. PARSONS.
